UNITED STATES PATENT OFFICE.

HENRY CHARLES FLETEMAYER, OF LAFAYETTE, INDIANA.

CAR-BRAKE.

SPECIFICATION forming part of Letters Patent No. 391,309, dated October 16, 1888.

Application filed August 15, 1888. Serial No. 282,821. (No model.)

To all whom it may concern:

Be it known that I, HENRY CHARLES FLETEMAYER, of Lafayette, in the county of Tippecanoe and State of Indiana, have invented certain new and useful Improvements in Car-Brakes; and I do hereby declare that the following is a full, clear, and exact description thereof, reference being had to the accompanying drawing, and to the letters of reference marked thereon, which form part of this specification, in which—

The figure represents an end view of a car to which my improved brake-setting devices are applied.

This invention is an improvement in car-brake-actuating devices; and its objects are to dispense with the use of brake wheels and drums to tighten the brake-chains, and instead to employ a system of levers for applying or releasing the brakes direct, the levers being arranged upon the end of the car in such manner that the brakes can be operated from either side or top of the car, the levers being so connected as to be operated simultaneously, so that the locking or release of one lever will lock or release the others.

Referring to the accompanying drawing by letter, A designates the car, and B is a vertical piece or block secured on the end of the car near the center thereof and extending about half the height of the car.

C is an upstanding lever pivoted on a bolt, D', between the upper end of a block, B, and a clip, d, secured to the block, as shown, so that the lever has lateral play.

E is a binding-plate secured to the end of the car in rear of lever C, and which tends to force the upper end of the lever away from the car and out of engagement with a rack, F, which lever C is adapted to engage by a tooth, e, being kept in position for engaging the rack by a strap, f.

G is a fulcrum-bar pivotally mounted on bolt D' and lying normally in a horizontal position when the brakes are released. The longest arm of this fulcrum-bar is connected by a link, g, with lever C, so that it may be operated thereby. In the lower edge of the long arm of bar G are a series of perforations, h, in which may be adjustably engaged the end of a hook-link, H, the other end of which is connected to the

draft-chain I, that operates the car-brakes, so that by lifting the long arm of bar G the brakes will be applied. The brakes are not shown, as they may be of any ordinary construction operated by a draft chain or link. By varying the point of attachment of link H to bar G the leverage exerted from said bar upon the draft-chain is varied.

K is a lever lying nearly horizontal and below bar G. Its inner end is pivoted at k upon a proper support, and its free end projects over block B to the opposite side of the car, where it is adapted to engage a rack, L, similar to rack F, and is guided by a strap, l, similar to strap f. M' is a link attached to lever K near the pivot thereof and connecting the same with the short arm of bar G, so that when the outer end of lever K is depressed the bar will be oscillated and the brake-chain tightened. The lever K bears against the outer face of block B, and will be thereby kept out of engagement with the teeth of rack L when not forcibly engaged therewith.

M is a lever similar to lever K but extending to the opposite side of the car. Its inner end is pivoted at m on block B, and it is connected by a link, M', to lever K, so that when its outer end is depressed the lever K and bar G will be actuated, as before described, and the brake-chain tightened. The levers C, K, and M, by their connections to each other and bar G, move simultaneously. Lever M is provided with a rack, O, and guard o, similar to the other racks and guards of the other levers, and also with a binding-plate, P, by which its free end is kept normally out of engagement with the rack.

From the foregoing it is obvious that, if either of the levers C, K, or M be actuated and locked to their rack, bar G is oscillated and the brake-chain tightened, thus applying the brakes, and the locking of one lever also locks the others, although they are disengaged from their racks. If the lever C has been locked by its rack, it could be unlocked by depressing either lever K or M sufficiently to throw lever C back out of engagement with its rack. The brakes can thus be applied or released from either side or top of the car, no matter which lever is employed, or engaged with its rack.

The outer end of the longer arm of bar

G may be weighted to hasten the release of the brakes when the levers are unlocked, as shown at Q; or a spring may be employed, as shown at R. The effect of the weight or spring is 5 obvious, and the operation of the parts is apparent from the foregoing.

I do not claim, broadly, in this application any of the features shown in my application, Serial No. 278,836, filed July 2, 1888; but

10 What I do claim is—

15 1. The combination of a horizontal oscillating bar pivotally mounted on the end of a car and provided with a series of perforations in the lower edge of its longer arm, and the device for returning said bar to normal position, with the link attached to said bar and to the 20 brake-chain, and the series of levers connected with said bar, and the racks and guards for said levers at the top and sides of the car, all 25 substantially as specified.

2. The combination of the pivoted levers extending, respectively, to the top and opposite sides of the car, and the racks and guards therefor, and the binding-plates for said levers, 25 with the pivoted oscillating bar operated by

said levers and having its longer arm connected with the brake-chain, substantially as and for the purpose specified.

3. The combination of the vertical block, the upstanding lever pivoted to the upper end 30 thereof, its rack and binding-plate, and the oscillating bar pivoted on the upper end of said block and having its long arm connected with the upstanding lever and with the brake-chain, and the device for returning said bar to 35 normal position, with the horizontal levers pivoted below the bar, the upper one being connected to the short arm of the bar and the lower one being connected to the upper, whereby by all the levers and bar move together, and 40 by the racks and guards for said levers, all substantially as described.

In testimony that I claim the foregoing as my own I affix my signature in presence of two witnesses.

HENRY CHARLES FLETEMAYER.
